CLAIM

The ornamental design for a combination card and key holder, as shown and described.

DESCRIPTION

FIG. 1 is a perspective view of the combination card and key holder in accordance with the invention, the dashed lines forming no part of the claimed design;

FIG. 2 is a top elevation view thereof, the dashed lines forming no part of the claimed design;

FIG. 3 is a front elevation view thereof, the dashed lines forming no part of the claimed design;

FIG. 4 is a left side elevation view thereof, the dashed lines forming no part of the claimed design;

FIG. 5 is a bottom elevation view thereof, the dashed lines forming no part of the claimed design;

FIG. 6 is a perspective view thereof, showing the key tags fanned out for viewing, the dashed lines forming no part of the claimed design; and,

FIG. 7 is a front elevation view thereof, showing the key tags fanned out for viewing, the dashed lines forming no part of the claimed design.
